US0D1088602S

(12) **United States Design Patent** (10) **Patent No.:** **US D1,088,602 S**
(45) **Date of Patent:** **** Aug. 19, 2025**

(54) **CHAIR**

(71) Applicant: **Zibin He**, Dongguan (CN)

(72) Inventor: **Zibin He**, Dongguan (CN)

(**) Term: **15 Years**

(21) Appl. No.: **29/924,199**

(22) Filed: **Jan. 18, 2024**

(30) **Foreign Application Priority Data**

Dec. 27, 2023 (CN) 202330860157.1

(51) **LOC (15) Cl.** **06-01**

(52) **U.S. Cl.**

USPC **D6/366**

(58) **Field of Classification Search**

USPC D6/366, 716, 716.1–716.6, 708.23, 360,

D6/380, 379, 708.24, 364

CPC A47C 3/12; A47C 3/026; A47C 7/462;

A47C 7/46; A47C 7/54; A47C 7/006

See application file for complete search history.
